(57) CLAIM

The ornamental design for a garment, as shown and described.

DESCRIPTION

FIG. 1 is a front view of a garment showing my design;

FIG. 2 is a rear view thereof;

FIG. 3 is a first side view thereof;

FIG. 4 is a second side view with an arm in a raised position;

FIG. 5 is a front first side perspective view with arms in a downward position; and,

FIG. 6 is a rear side perspective view thereof.

The long-and-short broken lines immediately adjacent shaded areas form an unclaimed boundary, and form no part of the claim.

The even-length broken lines are directed to environment, represent unclaimed subject matter, and form no part of the claimed design.

The contrast in shading represents a contrast in appearance only and does not represent any particular color, material, texture, or finish.
